BROTHERS, OF TOPEKA, KANSAS.

BED-SPRING.

1,203,096.

Specification of Letters Patent.

Patented Oct. 31, 1916.

Application filed March 12, 1915. Serial No. 13,962.

To all whom it may concern:

Be it known that I, CHARLES D. BROUYETTE, a citizen of the United States, residing at Topeka, in the county of Shawnee and 5 State of Kansas, have invented certain new and useful Improvements in Bed-Springs, of which the following is a specification.

My invention relates to a bed spring, wire bed bottom, or like flexible structure for 10 supporting the mattress or pad in a bed, couch or cot; and the principal object of the invention is to provide a bed spring, or equivalent structure, with means for holding the mattress or pad in place, which, being 15 cause of its simplicity, will add little or nothing to the expense of manufacturing the spring and will not make a spring provided therewith any more cumbersome or more difficult to pack, ship or otherwise han- 20 dle than the ordinary bed spring.

The invention is illustrated in two somewhat different embodiments, in the accompanying drawings wherein—

Figure 1 is a view, in perspective, of a 25 link fabric bed spring provided with the mattress holding device of my invention. Fig. 2 is a detail view of the device. Fig. 3 is a view, in perspective, of a spiral spring bed bottom constructed in accordance with 30 the invention, and Fig. 4 is a sectional view taken on line 4—4 of Fig. 3.

Like characters of reference designate like parts in the several figures of the drawings.

Referring first to Figs. 1 and 2, 10 indicates the end rails of the supporting frame of a wire mattress or bed spring, and 11 the side rails. The fabric is shown as made up of a plurality of wires 12, each bent to form a 15 series of V's, the apexes of which are provided with hooks 13 which engage the apexes of the V-shaped bends of adjacent wires. The end wires are secured to the end rails 10 of the frame by means of helical 20 springs 14. The fabric is completed by a pair of lateral marginal wires 15 engaged in any suitable manner by wires 12. These 25 marginal lateral wires are provided with upstanding projections which are preferably 30 constituted by bending the wires to form off-sets 16. These off-sets keep the mattress from slipping off the spring. At the same 35 time they add little or nothing to the ex-

pense of manufacturing the spring and are no inconvenience in the matter of shipping 55 or otherwise handling the spring. The engagement of the wires 12 with the marginal wires 15 is preferably between each off-set. The marginal wires 15 are preferably kept taut by helical springs 14^a which, in each 60 case, engage the adjacent end rail 10 and a bend 17 formed in the wire. Beyond the bend 17 the wire is formed with an inward horizontal offset 18, the end of the wire being anchored to the end rail in any suitable 65 manner. For instance, it may be attached to one of the helical springs 14. By this means the lateral marginal wires 15 are held so that the offsets 16 are in substantially vertical position. It will be understood that 70 the invention is not limited to the particular kind of fabric described, which is of familiar construction except so far as concerns the lateral marginal wires.

The same expedient may be applied to a 75 spring or bed bottom in which spiral springs are employed. This is shown in Figs. 3 and 4. 19 designates a supporting structure of any preferred construction for the spiral springs 20. The upper ends of the springs 80 are secured to a rectangular wire structure 21 provided with intermediate longitudinal wires 22 and cross wires 23. The lateral marginal wires 24 of the rectangular structure are formed with upstanding off-sets 25, 85 which keep the mattress 26 in position, as shown in Fig. 4.

In the claims I have used the term "bed spring" in a generic sense as covering any bed bottom, couch bottom, wire mattress, or other like flexible, resilient structure for supporting a mattress, pad, or the like. The term "mattress" is likewise intended to cover a pad or similar article of bedding supported on the spring. 95

I claim:

1. In a bed spring, a rigid frame consisting of end rails and side rails, a reticulated wire fabric, helical springs supporting the fabric on said end rails, lateral marginal 100 wires engaged with said reticulated fabric at intervals and formed between the points of engagement with upstanding off-sets, and with horizontal inturned off-sets at their extremities, means for anchoring the extremities of the wires to said end rails, and helical 105

springs interposed between the horizontal off-sets of the lateral marginal wires and said end rails.

2. In a bed spring, a flexible fabric comprising marginal wires which are interwoven with and form parts of said fabric, extend continuously the length of the bed

spring on opposite sides thereof, and are bent at intervals to provide upstanding offsets to keep the mattress in place.

CHARLES D. BROUYETTE.
